UNITED STATES PATENT OFFICE.

OTTO RUZSICKA AND GEORGE M. LAUB, OF NEWARK, NEW JERSEY.

COIN-CONTROLLED VENDING-MACHINE.

1,171,543.

Specification of Letters Patent. Patented Feb. 15, 1916.

Application filed June 17, 1915. Serial No. 34,570.

To all whom it may concern:

Be it known that we, OTTO RUZSICKA and GEORGE M. LAUB, citizens of the United States, residing in the city of Newark, in the county of Essex and State of New Jersey, have invented certain new and useful Improvements in Coin-Controlled Vending Machines, of which the following is a full, clear, and exact description, such as will enable others skilled in the art to which it pertains to make, construct, and use the same, reference being had to the accompanying drawings, and to numerals of reference marked thereon, forming a part of this specification.

The invention relates to coin-controlled vending machines, and particularly to that class of automatic vending machines in which coins of predetermined dimensions are inserted through a slot and deposited in a suitable ejector, and through the intervention of which, a package or other article of merchandise to be vended, is ejected by the operation of the machine.

The objects of the invention are to provide a simple and practical form of automatic vending machine, which will be particularly well adapted for attachment to the backs of chairs, such as are used in theaters, cars and the like, to provide an apparatus which will be sure to deliver a package of merchandise in return for the coin after the same has been once inserted, and further to so arrange the parts as to prevent the insertion of a coin at such times as when there are no packages in the machine to be vended.

Other objects will appear from the description hereinafter given, and our invention consists in the combinations and arrangements of parts, which will be herein-after fully described, and specifically defined in the appended claims.

In the drawings forming a part hereof, Figure 1 represents a front elevation of our improved device secured to a supporting plate designed to be secured to the back of a seat, chair or the like. Fig. 2 represents in section, a side elevation of the device taken on lines $x-x$ in Fig. 1, looking in the direction indicated by the arrow. Fig. 3 represents a front elevation of the device, the front plate of the machine being removed and parts broken away from the delivery chute. Fig. 4 represents a perspective view of the combined weight for the

packages and a locking device to close the coin passage, thus preventing the insertion of another coin when the machine is empty; and Fig. 5 represents a fragmentary perspective view of the spring-actuated coin carrying member, which together with the coin, serves to eject the lowest package from beneath the packages of merchandise which are arranged one above the other.

Similar numerals of reference refer to like parts throughout the specification and drawings.

In the drawings, 1 represents the main body of the case of the machine, which may be of any material and of any desired shape or configuration, that shown in the drawings being provided with a reclining front, to which a detachable front plate 2 is secured by means of a screw-bolt 3 or the like as clearly indicated. A rectangular lug 4 formed near the upper end of the plate 2, is designed to be received into a slot located near the front edge of the top of the case 1 and which serves to position the front plate on the case of the machine.

An integrally-formed receiving ledge 6 extends outwardly from the lower edge of the front plate 2, in close proximity to a discharge opening 7, through which the goods to be vended, are discharged, and above the discharge opening 7 a sight-glass 5 is provided, to see the interior of the machine to ascertain whether the machine is provided with packages or if it be empty. A supporting plate 8, having holding means, as for instance, headed studs 9, designed to be received into suitable apertures 10 formed in the rear wall of the case 1, is provided, whereby the machine may be secured to a car or theater seat, and the lock latch 11 of the lock 12, which is also secured to the supporting plate 8, engages with a suitable slot in the top of the case, in order to positively lock the machine in position on said supporting plate.

Secured to the interior of the case 1 in any convenient manner, is the package compartment 13, in which the packages of merchandise to be vended, are arranged one above the other. A coin chute 14 is located on the rear of the package compartment 13, which registers with the coin slot 15 located in the side of the case 1, and extending from the under and front side of the compartment 13, is a delivery chute 16, which communicates with the discharge opening 7 in the

front plate 2, and by means of which the packages are deposited on the receiving ledge 6.

A spring-actuated, coin-carrying member 5 and ejector is pivotally secured to the upper outside portions of the sides of the package compartment 13, by means of the arms 18-18, which are rigidly secured to a tube 19 rotatively mounted in the upper portion 10 of the compartment 13. Between the lower ends of the said arms 18-18, is a coin-receiving compartment 20. Depending from the rear of the package compartment 13 is a stop 21, against which the coin compartment 20 of the spring-actuated, coin-carrying member is held by the spring 22, one end 15 of which is secured to the inside of the package compartment 13, near the upper edge thereof, and the other end of which engages with one of the arms 18, to normally hold the coin compartment 20 against the stop 21, so that the opening in the coin compartment registers with the coin chute 14, so that when a coin is inserted in the coin 20 slot 15, it passes into the coin chute 14, and from there into the coin compartment 20 of the spring-actuated coin carrying member.

Secured to the stop 21 and extending at right-angles therefrom, and in close proximity to the under side of the coin compartment 20, is a ledge 23, which limits the further movement of the coin after it has been received into the coin compartment 20 and serves to keep it there.

35 A shaft 24, provided with a knob 25, is secured in the tube 19, by means of a set screw 26, the shaft passing through apertures in the upper end of the case 1, and the knob being located outside of the case, 40 so that by rotating the knob, the spring-actuated, coin-carrying member is operated.

One-half of the lowermost package is supported on a pair of lugs 17, extending forwardly from the rear wall of the package 45 compartment, and directly above said lowermost package, extend two guides 40, which are integrally formed on the side walls of the package compartment 13, and which serve to hold the packages in their proper 50 position.

In order that the device should operate in as noiseless a manner as possible, pieces of felt 28 are secured to the stop 21, and to the rear of the delivery chute 16, which are 55 designed to be engaged by the coin compartment during its forward and rearward movement, and which limits the movement thereof.

29 represents a combined weight for the 60 packages and a locking device, the same comprising a plate 30, designed to rest upon the top package, the front of the plate being provided with a flange 31, with the word "Empty" thereon, designed to have sliding 65 engagement with the inside of the guides

formed on the front of the package compartment 13. Secured to the plate in any convenient manner, and extending upwardly therefrom, is a stud 32, carrying a spring-actuated pawl 33, the front end of the pawl being provided with an engaging element 34, designed to engage with an aperture 35 formed in the rear wall of the package compartment 13, so that when the last package is ejected from the machine, the engaging 70 element 34 of the pawl 33 will enter the aperture 35 located in the rear wall of the package compartment 13, and project sufficiently into the coin chute 14 located on the rear of the package compartment, thereby closing 75 the coin passage, thus preventing the insertion of another coin when the machine is empty.

The operation of the device is as follows: In order to fill the machine, the lock is manipulated, thereby releasing the latch bolt 11 from the slot in the top of the case 1, and the operator is then enabled to remove the machine from the supporting plate 8, by disengaging the case from the headed studs 9 80 located on the supporting plate. The removal of the screw bolt 3 permits the separation of the detachable front plate 2 from the case 1. Thereafter, the engaging element 34 of the spring-actuated pawl, which 85 is carried by the combined weight and locking device 29, is withdrawn from the coin 90 passage 14, and the required number of packages of merchandise to be vended, are arranged in the package compartment 13, 100 one above the other. After the detachable front plate 2 has been secured to the case of the machine, and the machine thereafter located in position on the supporting plate, a coin inserted in the coin slot 15 will pass 105 into the coin chute 14, and from there drop into the coin-receiving compartment 20 of the spring-actuated, coin-carrying member. It will thus be seen that the lower end of the coin rests upon the ledge 23, which extends at right-angles from the stop 21, and the upper edge of the coin projects sufficiently above the coin compartment 20 to engage the lowermost package and shove it forward and out from beneath the pile, 110 when the spring-actuated, pivoted coin-carrying member is moved forward by turning the knob 25 of the shaft 24, which is secured to the tube 29 rotatably mounted in the upper end of the case 1 and which passes 115 through the package compartment 13. When the coin compartment 20 of the coin-carrying member has reached the limit of its forward stroke, shown in dotted lines in Fig. 2, and thereby discharged the said 120 package, the coin is released from the coin compartment, and falls off the ledge 23 into the case of the machine. The spring 22 then returns the coin-carrying member and holds the coin-receiving compartment 20 in 125 130

its normal position against the stop 21. When the last package is ejected from the machine, the engaging element 34 of the pawl 33 will enter the aperture 35 located in the rear wall of the package compartment 18, and project sufficiently into the coin chute 14 located on the rear of the package compartment, thereby closing the coin passage, thus preventing the insertion 5 of another coin when the machine is empty. The package thus ejected passes down the delivery chute 16, and out through the discharge opening 7 with which it communicates, and is deposited on the receiving 10 ledge 6. The top of the coin compartment 20 is located a trifle below the under side of the lowermost package in the package compartment, so that upon the return movement of the coin compartment, after the coin 15 has been discharged therefrom, the said top of the coin compartment will not interfere with the next lowest package.

It will thus be seen that the organization above described is a highly efficient one, and 20 while we have shown the preferred embodiment of our present invention, we do not wish to be limited to the exact details of construction and combination shown and described, as obvious modifications thereof will 25 appear to those skilled in the art, and such departures we consider within the scope and terms of our claims.

We claim:

1. A coin-actuated vending machine, comprising a case provided with a coin slot, a 30

package compartment, a combined weight and locking device movably located in said package compartment, comprising an angled plate, a spring-actuated, pivoted pawl carried by said plate, the free end of said pawl 40 adapted to be moved into registry with an aperture formed in the package compartment and to further project into a coin chute located on the rear of said package compartment after the last package has been 45 discharged, in order to prevent further coins from being inserted therein.

2. A combined weight and locking device for coin-actuated vending machines, comprising in combination with a case and its 50 actuating parts, an angled plate, said plate adapted to be movably mounted in the package compartment of said machine, a spring-actuated pawl pivotally secured to a stud carried by said plate, the free end of said 55 pawl being provided with an engaging element, designed to engage with an aperture formed in the package compartment and further projecting into a coin chute located on the rear of the package compartment 60 after the last package has been discharged, in order to prevent the insertion of further coins.

This specification signed and witnessed this 15th day of June, 1915.
